THE NORRIS PETERS CO., PHOTO-LITHO., WASHINGTON, D. C.

UNITED STATES PATENT OFFICE.

HARRY M. SALYER, OF NEW YORK, N. Y., ASSIGNOR TO THE FIRM OF
LUDWIG AND COMPANY, OF NEW YORK, N. Y.

SELF-PLAYING ATTACHMENT FOR MUSICAL INSTRUMENTS.

SPECIFICATION forming part of Letters Patent No. 700,829, dated May 27, 1902.

Application filed April 27, 1901. Serial No. 57,794. (No model.)

To all whom it may concern:

Be it known that I, HARRY M. SALYER, a citizen of the United States, and a resident of the city of New York, borough of the Bronx, in the county of New York and State of New York, have invented certain new and useful Improvements in Self-Playing Attachments for Musical Instruments, of which the following is a specification.

10 This invention relates to improvements in automatic playing attachments for musical instruments; and the object of my invention is to provide a new and improved attachment of this kind which is simple in construction, 15 strong and durable and reliable, and very effective in use.

In the accompanying drawings, in which like letters of reference indicate like parts in all the figures, Figure 1 is a front elevation of 20 my improved automatic playing attachment, parts being in section and others broken away and some omitted. Fig. 2 is a vertical longitudinal sectional view through one of the 25 pneumatic key-striker-actuating mechanisms with its valves. Fig. 3 is a vertical longitudinal sectional view through the compressed-air-controlling valve. Fig. 4 is a detail view of the suction-controlling valve. Fig. 5 is a 30 vertical transverse sectional view on the line 5 5 of Fig. 1. Fig. 6 is an enlarged detail elevation of the mechanism for reversing the music or note sheet rolling gear and controlling the admission of motive power to the various 35 pneumatic mechanisms in the attachment, parts being in section. Fig. 7 is a plan view of the same, parts being in section. Fig. 8 is an enlarged detail elevation of the note-sheet- 40 rolling gear, parts being in section. Fig. 9 is a side view of the same, parts being in section. Fig. 10 is a vertical transverse sectional view through the bridge or tracker-bar. Fig. 45 11 is a sectional view of the same on the line 11 11 of Fig. 10. Fig. 12 is an enlarged sectional view of the three-way cock. Fig. 13 is a plan view of a modification of certain parts. Fig. 14 is a detail longitudinal sectional view 50 of the note-sheet roller. Fig. 15 is a detail view of the tubes to the controllers. Fig. 16 is a longitudinal sectional view of the tracker- bar and parts connected therewith. Fig. 17

is a vertical transverse sectional view of the same.

The keys A and A', Fig. 5, of the keyboard are actuated by key-strikers placed above them, and each key-striker has a rod A², the upper end of which is rested against a diaphragm A³, held in a casing A⁴, in the bottom of which said rod A² is guided. The rod A² is pressed against the diaphragm A³ by a helical spring A⁵, surrounding the rod. The upper end of the casing A⁴ has a duct A⁶, through which compressed air can be admitted into the top of the casing A⁴ above the diaphragm A³ to force down the latter and the rod A². Valve mechanisms, which will be described directly, govern the admission of compressed air.

Pneumatic mechanisms such as first described are used for various other purposes in my improved automatic playing attachment and will be referred to hereinafter as "pneumatic mechanism." Each pneumatic mechanism, whether used for operating a key-striking rod or otherwise, has the top of its casing A⁴ connected with a block A⁷, in which the duct A⁶ is formed, and this duct leads to a large horizontal bore A⁸ in the block A⁷, and at each end of this bore a valve-seat is formed for the valves A⁹ and A¹⁰ on opposite ends of a stem A¹¹ in said bore. The block A⁷ is located between two air-chambers B and C, the former containing compressed air and the latter air rarefied to a greater or less degree. A hollow plug B' is screwed through the chamber B at each pneumatic key-operating mechanism and is in communication with the chamber B, and its inner open end, communicating with the block A⁷, can be closed by a valve B² on a stem B³, secured at its opposite end to a diaphragm B⁴, held by a cap B⁵ on the outer end of the plug B'. This cap B⁵, Fig. 2, is connected with tubes B⁶ for conveying compressed air to the diaphragm and pressing it to the left for the purpose of opening the valve B² to a greater extent, so as to admit more compressed air than usually to the pneumatic mechanism, such tubes extending to suitable controllers K', which need not be described in detail, as they form no part of the present invention. The tubes B⁶ and plugs B' are provided only for those pneumatic

mechanisms that are used for operating key-strikers. Whenever the valve A^{10} is lifted off its seat and communication thus established between the top of the casing A^4 and the inner end of the corresponding plug B' , the air-pressure in the chamber B can force the valve B^2 off its seat, permitting the compressed air to pass into the top of the casing A^4 and to act on the diaphragm A^3 and continue so to act as long as the valve A^{10} is held open.

At each pneumatic mechanism a hollow plug C' is passed through the chamber C and is in communication therewith and terminates at its outer end in a cup C^2 , in which a diaphragm C^3 is held by a cap C^4 , from which a tube C^5 extends to a tracker-board O . A stem C^6 is mounted to slide longitudinally in the plug C' , and one end, provided with a suitable head, rests against the diaphragm C^3 , and the other end rests against a diaphragm C^7 , secured in the cup C^8 , formed on the block A^7 , and against this diaphragm C^7 an extension C^9 of the valve-stem A^{11} rests.

C^{10} is a vent-opening in the cup C^8 .

Whenever the tube C^5 is opened by a hole in the note-sheet a , moved over the tracker-bar O , as will be set forth hereinafter, atmospheric-air pressure can act on the diaphragm C^3 and force the same to the right, Fig. 2, as a much-reduced pressure exists in the chamber C and cup C^2 , and thereby the diaphragm C^7 and the stem A^{11} are forced to the right, and the valve A^9 is seated and the valve A^{10} unseated. The compressed air can now act on the diaphragm A^3 in the casing A^4 , as hereinbefore stated. When the valves A^9 and A^{10} are again brought into the positions shown in Fig. 2, the air can escape from the casing A^4 through the duct A^6 and vent C^{10} , when the diaphragm A^3 is forced up by its spring A^5 . The controllers are each connected with the pneumatic mechanism for the keys of like denomination in each octave and also with the pneumatic mechanism of the keys which are usually not played with the first-mentioned keys, and each controller has a duct leading to the tracker-bar. Whenever a hole in the note-sheet registers with a duct leading to a controller, the valves B^2 of all valve mechanisms connected with the controller will be affected in the manner previously described; but this will have effect only in such pneumatic mechanisms in which the valve A^{10} has been opened at the same time. The compressed air is preferably stored in a tank D , Fig. 5, and may be produced by foot-power or any suitable motor. It is conducted through a tube D' , which is screwed into a neck D^5 of a governing valve-casing D^2 . The casing D^2 has a partition D^3 , from which a hub D^4 projects downward, and in the said hub a chamber D^6 is formed, which is open at the bottom and is in communication with the neck D^5 . The open end of the chamber D^6 can be closed by a valve D^7 , secured on a stem D^8 , passing longitudinally through the hub D^4

and secured at its upper end to a diaphragm D^9 , held on the top of the casing D^2 by a cap D^{10} , having a neck D^{11} . A duct D^{12} in the valve-stem D^8 establishes communication between the space above and below the diaphragm D^9 , and this duct can be adjusted in size by a screw D^{13} in said stem. A hole D^{14} in the partition D^3 connects the space below the diaphragm D^9 with the neck D^{15} . A tube D^{15} is screwed into a neck D^{16} , which is in communication with the lower part of the casing D^2 , and said tube D^{15} conducts the compressed air to the various pneumatic mechanisms to be operated by compressed air. When the neck D^{11} or a tube connected with the same is closed, so that the compressed air cannot escape, the same air-pressure exists on both sides of the diaphragm D^9 , and thus the valve D^7 is held in equilibrium, and the downward pressure of the compressed air on the valve is sufficient to open it, thus permitting the compressed air to pass into the tube D^{15} . Whenever the neck D^{11} or a tube d^2 , connected with the same, is opened by opening a cock W , connected with said tube, the compressed air can readily escape from above the diaphragm D^9 , and the now greater pressure on the under side of the diaphragm holds the valve D^7 closed.

An exhaust-bellows E or analogous device is connected with a suction-tube E^3 and with a discharge-tube E' , and said suction-tube is connected with a valve-casing E^2 , which is constructed like the valve-casing D^2 and has a valve E^4 arranged in a like manner, with the difference, however, that a downward extension E^5 of the valve-stem rests upon a diaphragm E^6 , secured on the bottom of the casing E over a hole E^7 in said casing E^2 . As long as the neck in the top of the casing E^2 or a tube connected with said neck remains closed the valve E^4 remains in equilibrium, as the air-pressure on both sides of the diaphragm in the casing E^2 is the same. Whenever the neck in the top of the casing E^2 or the tube connected therewith is open to the atmosphere, the air-pressure on the top of the diaphragm in the casing E^2 will preponderate and hold the valve E^4 open, and the extension E^5 of the valve-stem forces down the diaphragm E^6 more or less. As soon as the said neck or the tube connected therewith is closed the equilibrium is established and the external air-pressure, acting on the diaphragm E^6 , presses the valve E^4 on its seat instantly, and thus suction is cut off from all mechanism connected with the casing E^2 or suction-tubes connected therewith, and all mechanisms depending on such suction do not and cannot be operated until the valve E^4 is again open, excepting the tube E^{16} , as this tube is connected with the suction-tube E^3 in advance of the valve-casing E^2 .

The tube F' , having a controlling-cock F^2 , conducts compressed air from the tube D^{15} to the compressed-air motor F , which may be of any approved construction. By means of

suitable connections the motor F rotates the belt-pulley F³, mounted loosely on the shaft F⁴, projecting from an upright partition G. A driving-belt F⁵ passes over the pulley F³ and over a pulley F⁶, mounted loosely on a shaft F⁷, also mounted in the partition G and a bracket-frame G' on the same. The pulley F⁶ has fixed to it a pinion F⁸ and a peripherally-grooved collar F⁹ for receiving the rim of a disk F¹⁰, fixed on the end of a rod F¹¹, guided in the bracket-frame G' to move lengthwise. The playing-roll H, on which the note-sheet a is rolled while playing, is supported at one end and rotated by a short shaft G³, mounted in the partition G and bracket-frame G', and this shaft G³ carries a loosely-mounted cog-wheel G⁴, which is engaged with the pinion F⁸, and to the said cog-wheel a peripherally-grooved collar G⁵ is attached, into the groove of which the rim of the disk F¹⁰ also extends. The collar G⁵ is provided on its outer face with a clutch-pin G⁶, which can engage a clutch-pin G⁷ on a disk G⁸, fixed on the shaft G³. The pulley F⁶ is provided on its outer face with a clutch-pin G⁹, which can engage a clutch-pin G¹⁰ on the hub of a belt-pulley G¹¹, mounted on the shaft F⁷. A driving-belt G¹² is passed over the pulley G¹¹ and over the pulley G¹⁴, fixed on the short shaft G¹³, mounted in the partition G and serving to support one end of and to rotate the music-roll I, from which the note-sheet is unrolled for playing. The pulley F⁶ is constantly rotated and when pushed to the right, so that the clutch-pins G⁹ and G¹⁰ engage, rotate the pulley G¹⁴ at high speed, and the played note-sheet is re-rolled at high speed back upon its original roller I, from which it was unrolled while playing. When the pulley F⁶ is shifted to the left, Fig. 8, so that the clutch-pins G⁶ and G⁷ are engaged, the shaft G³ is rotated at a much-reduced speed, as motion is transmitted from the pulley F⁶ to the shaft G³ by means of the pinion F⁸ on the driving-shaft and the cog-wheel G⁴ on the driven shaft. The note-sheet a is thus rolled at ordinary playing speed upon the roller H, driven by the shaft G³. The rod F¹¹ is pivoted to the upper end of an upwardly-projecting arm J' of a rock-bar J, mounted on an arm J² on the upper end of a standard J³. Below each end of said rock-bar a pneumatic mechanism J⁴ or J⁵ is fixed in such a manner that the rods A² of said pneumatic mechanisms can be forced upward, and thus force either end of said rock-bar J upward. By operating one or the other of said pneumatic mechanisms the rod F¹¹ is shifted lengthwise in one direction or the other, and thus the roller H or I thrown in gear with the motor for moving the note-sheet a in one direction or the other. As shown in Fig. 7, the pneumatic mechanisms J⁴ and J⁵ are connected with a compressed-air chamber J⁶ and a rarefied-air chamber J⁷. A suction-tube b extends from the valve mechanism of the pneumatic mechanism J⁴ to a cock J⁸, (marked "reroll" in Fig. 1,) and a branch tube b' extends from the tube b to a hole in the tracker-bar O, as is also shown in Fig. 1. 70 A tube b² extends from the valve mechanism of the pneumatic mechanism J⁵ to the tubular bearing H⁶ of the roll H, which bearing will be described in detail later on. A rocking bar L is connected by the sleeve L' with the rocking bar J, so as to rock with it, the bar L being shorter than the bar J. Below the ends of the bar L valve-casings M and N are located, which are connected by the tubes d² and e² with the valve-casings D² and E², respectively. The casing M contains a downwardly-seating puppet-valve M', having a stem M² projecting from the top of the casing M. The valve M' is pressed from its seat by a spring M³, which automatically opens or lifts the valve. A duct M⁴ extends from above the valve-seat to the surface of the casing, and through it air can enter the casing when the valve is raised. The casing N contains an upwardly-seating puppet-valve N', having a stem N² projecting from the top of the casing N. The valve N' is pressed upward against its seat by a spring N³, which automatically closes said valve. A duct N⁴ extends from above the valve-seat to the surface of the casing, and through it air can enter the casing when the valve is open. Both valves M' and N' are open at the same time or closed at the same time. When the right-hand end of the bar L swings down, it closes the valve M' and permits the valve N' to close, and when the left-hand end swings down it opens the valve N' and permits the valve M' to open. 80 85 90 95 100 105 110 115 120 125 130

The tracker-bar O has a slightly-convexed top and is provided with a row of ducts f, which are connected with the various tubes leading to the various valve mechanisms. Each duct f is connected by a duct g with a chamber O' in the tracker-bar, and each duct g can be adjusted in size by a screw O². Six 110 of the ducts f are connected with ducts h, extending to the face of the tracker-bar O, as shown in Figs. 10 and 11, and these six ducts are connected with tubes m, leading to the six controllers K'. A bar P is guided to slide 115 lengthwise on the face of the tracker-bar by screws P', passed through longitudinal slots P² in the bar P into the front of the tracker-bar. Springs P², surrounding the screws P', press the said bar P against the front of the 120 tracker-bar. The bar P has six holes j, which can register with the six ducts h in one position of the bar P. One end of the sliding bar P is connected with a rod P⁴, which at its other end is pivoted to a lever P⁵, pivoted to the bracket-frame G', and which has its lower end pivoted to one end of a rod P⁶, the opposite end of which is pivoted to an upwardly-extending arm P⁷ of a rock-bar P⁸, pivoted to the standard J³. A pneumatic mechanism P⁹ is fixed under each end of the rock-bar P⁸ in such a manner that its rod A² can be forced upward to lift one end of the bar P⁸. The pneumatic mechanisms P⁹ are connected

with the compressed-air chamber J^6 and with the rarefied-air chamber P^{10} . Tubes h ; h' extend from the valve mechanisms of the pneumatic mechanisms P^9 to the tracker-bar O . 5 The tube K , connecting the rarefied-air chamber P^{10} with the suction-tubes K^2 , is provided with a shut-off cock K^3 . The chamber O' in the tracker-bar is connected by two tubes O^6 with a tube O^8 , connected with the casing of 10 a three-way cock O^4 , which is connected by the tube O^5 with the suction-tube K^2 and by the tube O^7 with the compressed-air tube D' . When the three-way cock O^4 is in the position shown in Fig. 12, the air is being constantly drawn out of the chamber O' and the ducts and the tubes connected therewith, and when the cock is turned half-way around the communication with the suction-tube is destroyed and communication established with 15 the compressed-air tube D' . The strong current produced forces the accumulated dust out of the chamber O' and the ducts f , g , and h .

The roller H has a bore H' extending from 20 its center to one end and a duct H^2 extending from the inner end of said duct H' to the surface of the roller. The bore H' extends also through the bearing-socket H^3 on the end of the roller H and can communicate 25 with the bore H^4 of a tubular bearing-pintle H^5 , mounted to slide lengthwise in a short tube H^6 in the partition G^2 . The tubular pintle H^5 is pressed toward the end of the roller H by a spring H^7 in the tube H^6 . The tube 30 b^2 is connected with the outer end of the tube H^8 , connected with the bearing-pintle H^5 . The six ducts f in the tracker-bar, which are connected with the ducts j , are also connected, as stated, by tubes m with six accentuation- 35 controllers K' , which in turn are connected by suitable tubes B^6 with the several pneumatic operating mechanisms for the key-strikers. The details of the controllers and accentuating mechanism form no part of the 40 present invention, and hence will not be described in detail. The roller I has a similar spring-bearing I' in the partition G^2 .

A compressed-air chamber R is connected by a tube R' with the tube D^{15} , and with said 45 chamber R three pneumatic mechanisms R^2 , R^3 , and R^4 are connected. The pneumatic mechanisms R^2 and R^3 serve for operating the rods R^5 and R^6 , which depress the "piano" and "forte" pedals. A spring-latch R^9 automatically locks the rod R^5 in lowered position with the piano-pedal depressed, and the 55 automatic mechanism R^4 serves for withdrawing the latch R^9 at the proper time to permit the spring R^{10} on the rod R^5 to throw the same upward. From each of the pneumatic mechanisms R^2 R^3 R^4 a tube n extends to the tracker-board O , and the tube n , connected with the pneumatic mechanism R^3 , has a three-way cock Q , which can be adjusted to shut 60 off by hand the tube n from the tracker-board and keep it open to the atmosphere. As long as this cock is held open to the atmosphere

the pneumatic mechanism R^3 holds the forte-pedal depressed. When the cock Q is adjusted to open the said tube n to the tracker-board, the said forte-pedal is only depressed, when a hole in the note-sheet a registers with that duct in the tracker-board that is connected with the said tube n . A cock S extends through all the six tubes m , so that by 70 turning said cock these six tubes can be closed to the tracker-board and will be cut out entirely, as far as any effect of the note-sheet is concerned. Each of said tubes m has a three-way cock S' , only one of which is shown, and 75 by means of these cocks each tube can be opened by hand to the outer air, and thus the controllers K' , connected with these tubes m , having the three-way cocks opened, will be constantly operative independent of any 80 holes in the note-sheet. By these means a player can accentuate the music played independently of the accentuating-holes in the note-sheet and according to his own tastes and inclinations. 85

A bar T is hinged at one end to the tracker-board O to extend lengthwise over the same and over the note-sheet, and on this bar the designations of the notes, &c., to which the various ducts f pertain are marked. 90

The operation is as follows: A note-sheet a , rolled on a roller I , is placed in its bearings—that is, the end of the shaft G^{13} and the bearing I' in the partition G^2 . The sheet a is passed over the tracker-bar and its end secured on stud V on the roller H . The cock W in the tube d^2 is in the position "Stop," and the said tube is now open to the atmosphere, and consequently the valve D^7 in the casing D^2 is closed, and no compressed air 100 can pass to the motor F or any compressed-air chamber or any pneumatic mechanism. The roller H is in gear with the motor, and the left-hand end of the rock-bar J is lowered and the right-hand raised. The valves M' 110 and N' are open. To start the instrument, the cock W is moved to the left ("Play") and is thus closed, permitting the valve D^7 to open, as previously explained, and to admit compressed air to the motor F , compressed-air 115 chambers, and at proper times—that is, when the corresponding valve mechanisms are operated—to the pneumatic mechanisms. The note-sheet a is now rolled on the roller H and closes the duct H^2 in the same and as the 120 note-holes in the note-sheets pass over the ducts f in the tracker-bar O permit air to pass to the valve mechanisms, as shown in Fig. 2, as the valve E^4 is held open as the tube e^2 , connected with the casing E^2 , is held open by 125 the lever L , permitting the pressure on the top of the diaphragm in the casing E^2 to press down the valve E^4 . Thereby the corresponding valves A^{10} are opened, and thus compressed air is admitted to the corresponding 130 pneumatic mechanisms and the keys are struck, and so on until the end of the tune is reached, at which time a hole in the note-sheet a registers with that tracker-bar duct f . 135

connected with the tube b' , and thus the pneumatic mechanism J^4 is operated, and the rock-bar J is thrown into the position shown in Fig. 6. Thereby the roller I or rerolling-roller is thrown in gear with the motor F , and the sheet is unrolled from the roller H upon the original roller I . At the same time that the gear is reversed the valve N' is closed, and the valve M' is also closed. By the closing of the valve N' the valve E^4 in the casing E^2 is closed in the manner previously described, and thus the suction cut off from all the valve mechanisms, excepting the mechanisms J^4 J^5 , by means of the tube E^{16} , as such mechanisms J^4 J^5 are connected by the tube E^{16} with the suction-tube E^3 in advance of the valve-casing E^2 . The closing of the valve M' has no effect, as the tube d^2 has already been closed by the cock W . All parts remain in this position until the note-sheet a is entirely rerolled on the roller I . When the end of the note-sheet uncovers the duct H^2 in the roller H , air can pass through the ducts H' H^2 in the roller H and the tube b^2 into the pneumatic mechanism J^5 . Thereby the roller I is thrown out of gear, the roller H in gear, the valve N' is opened, and the valve M' is also opened. The opening of the valve N' causes the opening of the valve E^4 in the casing E^2 , and all valve mechanisms are again connected with the suction device. The opening of the valve M' has no effect, as the tube d^2 is still closed by the cock W . The note-sheet a is thus alternately unrolled from and rolled upon the roller H , and while the sheet is being rolled upon the roller H the valves of the pneumatic mechanisms can be operated, as they are connected with the suction device, and thus the instrument can play; but when the sheet is being unrolled from the roller H —that is, rerolled upon the roller I —the valve mechanisms are cut out from the suction device, and the instrument does not play. This rolling and rerolling continues until the cock W is turned to right, whereby the tube d^2 is opened. As its end is held open by the valve M' during playing, the instrument stops at once. If the valve W is turned to "Stop" while a melody is being played the sheet and other parts retain the positions they had at the time the cock W was turned. If, however, the cock W is turned to "Stop" while the note-sheet is being rerolled upon the roller I , the instrument does not stop until the sheet is entirely rerolled upon the roller I , for the reason that as soon as such rerolling begins the valve M' closes the tube d^2 , and thus the opening of the cock W has no effect. When the sheet is entirely rerolled, the duct H^2 in the roller H is uncovered, and the air entering through the same causes a reversing of the rock-bar L by means of the pneumatic mechanism, the valve M' is raised, and the end of the tube d^2 opened, and the instrument is stopped. A fresh music-roll can be inserted and the instrument again started by the turning of the cock W to

"Play," thereby closing the tube d^2 , the end of which is held open by the valve M' . Whenever it is desired or necessary to reroll the sheet a after a greater or less part of it has been played, the reroll-cock J^8 is opened to the atmosphere. Thereby the pneumatic mechanism J^4 is operated and throws the rock-bar J into the position shown in Fig. 6 and the rerolling-roll in gear. The valves of the several pneumatic mechanisms are not operated now, as the valve N' has been closed, the valve E^4 also closed, and the suction requisite for the operating of these valve mechanisms has been cut off. As soon as the sheet is entirely rerolled the rolling-gear is reversed automatically, as stated. The valves N' E^4 are thereby opened and the instrument begins to play again unless the cock W has been turned to "Stop"—that is, the tube d^2 thereby opened. Whenever certain passages or parts are to be automatically accentuated independently of or with the effect of the forte or piano pedals, the bar P must be shifted to bring the six holes j in the same to register with the six ducts h . Thereby all the six controllers K' will be thrown in and remain active as long as the bar P is in this position. When this said effect is no longer desired, the bar P must be shifted to close the ducts h , as shown in Fig. 11. The said bar is shifted by means of the pneumatic mechanisms P^9 , from which the tubes k k' extend, to ducts f in the tracker-bar, the note-sheet having corresponding holes. The same effect can be produced manually by means of the three-way cocks S' in the several tubes m , as has been stated. If desired, the tube b' instead of leading to a duct in the tracker-bar may be connected with a hollow bearing for the roller I , like the bearing for one end of the roller H , the roller I having ducts corresponding to the ducts H' H^2 in the roller H . With the modified construction shown in Fig. 13 the sliding plate P and means for operating the same are dispensed with and the short ducts h in the tracker-board O are not provided. The pneumatic mechanisms P^9 can act on the rocking bar P^8 in the manner previously described to rock the same. A valve-plug U forms the pivot of the rocking bar P^8 and fits within a casing U' . The six tubes B^{10} , branching from the tubes B^6 leading to the controllers K' , lead to the casing U' and are continued at the other side of the casing, as at U^2 , this continuation having open ends U^3 . The plug U has six transverse bores U^4 , which when the plug is in one position establish communication between the ends of the tubes B^{10} in the casing U' and the open continuations U^2 of said tubes B^{10} . In the other position of the plug this communication is interrupted. When all notes are to be accentuated—that is, played with more force—a hole is so arranged in the music-sheet that at the proper time one of the pneumatic mechanisms P^9 throws the rock-bar P^8 in such position as to establish communica-

tion between the tubes B^{10} and their continuations U^2 , so that atmospheric air can pass to all the controllers, whereby the valves of all the pneumatic key mechanisms are so actuated as to admit more compressed air to each pneumatic key mechanism. When this accentuation is to cease, another hole in the note-sheet causes pneumatic mechanism P^9 to throw the rocking bar P^8 the other way, and thereby all tubes B^{10} are closed and any one note can be accentuated from the tracker-board in the manner previously described. In the construction shown in Fig. 13 the valve-casings M and N and the valves therein are omitted and the tubes d^2 and e^2 extend to a casing V' , in which a plug V is mounted to rock axially, which plug is attached to the rock-bar J and forms a pivot for the same. The plug V has two transverse ducts V^2 , which can establish communication between those ends of the tubes d^2 e^2 in the casing V' and continuations v v of the tubes at the other side of the casing, which continuations are open at their outer ends. For one position of the rock-bar J both tubes d^2 e^2 are open, and for the other they are both closed. The effect of opening or closing both tubes d^2 and e^2 is the same as that previously described.

Having described my invention, what I claim as new, and desire to secure by Letters Patent, is—

1. In a self-playing attachment for musical instruments, the combination with a note-sheet-rolling mechanism, of a reversing-gear for said sheet-rolling mechanism, pneumatic mechanism for operating the reversing-gear and means for controlling the pneumatic mechanism from a roller of the sheet-rolling mechanism, substantially as herein shown and described.

2. In a self-playing attachment for musical instruments, the combination with a note-sheet-rolling mechanism, of a reversing-gear for said sheet-rolling mechanism, pneumatic mechanism for operating the reversing-gear and means for pneumatically controlling the reversing-gear from a roller of the sheet-rolling mechanism, substantially as herein shown and described.

3. In a self-playing attachment for musical instruments, the combination with a note-sheet-rolling mechanism, of a driving-gear, a reversing-gear and means for controlling the reversing-gear pneumatically from a roller of the sheet-rolling mechanism, substantially as herein shown and described.

4. In a self-playing attachment for musical instruments, the combination with a note-sheet-rolling mechanism, of a driving-gear, a reversing-gear, pneumatic mechanism for operating the reversing-gear and means for pneumatically controlling said reversing-gear from a roller of the sheet-rolling mechanism by the unrolling of the sheet, substantially as herein shown and described.

5. In a self-playing attachment for musical instruments, the combination with two note-

sheet rollers, one of said rollers having a duct extending from one end of said roller to the surface of the roller, a driving-gear, a reversing-gear, pneumatic mechanism for operating the reversing-gear, and a pneumatic connection between the said pneumatic mechanism and the said duct in the roller, substantially as herein shown and described.

6. In a self-playing attachment for musical instruments, the combination with two note-sheet rollers, one of said rollers having a duct extending from one end to the surface of the roller, a tubular bearing for that end of the roller having the duct, a driving-gear, a reversing-gear, pneumatic mechanism for operating the reversing-gear and a pneumatic connection between the said tubular bearing and the pneumatic mechanism for operating the reversing-gear, substantially as herein shown and described.

7. In a self-playing attachment for musical instruments, the combination with two note-sheet rollers, one of said rollers having a duct extending from one end to the surface of the roller, a spring-pressed tubular bearing for that end of the roller having the duct, a driving-gear, a reversing-gear, pneumatic mechanism for operating the reversing-gear and a pneumatic connection between the said tubular bearing and the pneumatic mechanism for operating the reversing-gear, substantially as herein shown and described.

8. In a self-playing attachment for musical instruments, the combination with two note-sheet rollers, one of said rollers having a duct extending from one end to the surface of the roller, a tubular spring-pressed bearing for one end of the said roller, a rotative bearing for the other end, a driving-gear, a reversing-gear, pneumatic mechanism for operating the reversing-gear and a pneumatic connection between the said tubular bearing and the pneumatic mechanism for operating the reversing-gear, substantially as herein shown and described.

9. In a self-playing attachment for musical instruments, the combination with a note-sheet-rolling mechanism, of a driving-gear for this rolling mechanism, a compressed-air-conducting tube, a valve in said tube, a suction-tube, a valve in said suction-tube, a reversing-gear for the rolling mechanism, means operated with said reversing-gear for controlling the valves in the compressed-air tube and suction-tubes and pneumatic mechanisms connected with said compressed-air tube and suction-tube, substantially as herein shown and described.

10. In a self-playing attachment for musical instruments, the combination with a note-sheet-rolling mechanism, of a driving-gear for this rolling mechanism, a compressed-air tube, a valve in the same, a suction-tube, a valve in the same, a separate tube connected with the casing of each of said valves, a controlling-valve in the end of each of said tubes, a reversing-gear for the roller-driving mech-

anism, means connected with the reversing-gear for actuating the valve in the ends of the said tubes and pneumatic mechanisms connected with the compressed-air tube and the 5 suction-tube, substantially as herein shown and described.

11. In a self-playing attachment for musical instruments the combination with a series of pneumatic mechanisms to be actuated 10 by compressed air, of a valve on each pneumatic mechanism, means for moving said valves by suction, a compressed-air-conducting tube, connected with the pneumatic mechanisms, a suction-tube connected with the 15 valve mechanisms of said pneumatic mechanisms, a valve in the suction-tube, a valve in the compressed-air-conducting tube, a note-sheet-moving mechanism, a driving-gear for the same, a reversing-gear and means connected 20 with the reversing-gear for controlling the valves in the suction-tube and in the compressed-air-conducting tube, while reversing, substantially as herein shown and described.

12. In a self-playing attachment for musical instruments the combination with a 25 tracker-bar having ducts and a chamber connected with each duct, of a tube extending to said chamber, a suction-tube and a compressed-air tube and a three-way cock connecting the tube extending to said chamber 30 with the suction-tube and the compressed-air tube, substantially as herein shown and described.

13. In a self-playing attachment for musical instruments, the combination with a 35 tracker-bar having ducts and a chamber connected with said ducts, of means of drawing air from said chamber and means for conducting compressed air into said chamber, 40 substantially as herein shown and described.

14. In a self-playing attachment for musical instruments, the combination with a 45 tracker-bar having ducts, of tubes connected with the ducts, a three-way cock connected with each of a series of such tubes and means in such tubes, between the ends of tracker-board ducts and the three-way cocks for closing such duct or tube connected therewith, substantially as herein shown and described.

50 15. In a self-playing attachment for mu-

sical instruments, the combination with a tracker-bar having ducts, and additional ducts extending from the first-mentioned ducts, means for opening and closing said additional ducts automatically, substantially as 55 herein shown and described.

16. In a self-playing attachment for musical instruments, the combination with a tracker-bar having ducts and additional ducts 60 extending from the first-mentioned ducts, of means for opening and closing said additional ducts automatically by a note-sheet moved over the tracker-bar, substantially as herein shown and described.

17. In a self-playing attachment for musical instruments, the combination with a 65 pedal-operating bar, of a pneumatic mechanism for operating said bar, a tracker-bar, a tube extending from the said pneumatic mechanism to the tracker-bar and a three-way 70 cock in said tube, substantially as herein shown and described.

18. In a self-playing attachment for musical instruments, the combination with a series of pneumatic mechanisms to be operated 75 by compressed air, of valve mechanisms for said pneumatic mechanisms, means for operating said valves by suction, a compressed-air-conducting tube, a valve-casing connected with said tube, a valve in said casing controlling said compressed-air-conducting tube, 80 a suction-tube, a valve-casing connected therewith, a valve in the same controlling the suction-tube, a note-sheet-rolling mechanism, a reversing-gear for the same, a tube connected 85 with the valve-casing of the compressed-air tube, a tube connected with the valve-casing of the suction-tube and means for opening or closing said two tubes together automatically, which means are operated with 90 the reversing-gear, substantially as herein shown and described.

Signed at New York city, in the county of New York and State of New York, this 9th day of March, A. D. 1901.

HARRY M. SALYER.
